UNITED STATES PATENT OFFICE.

JOHN C. FARLEY, OF ENNIS, TEXAS, ASSIGNOR OF ONE-THIRD TO HYMAN PRINCE, OF HOUSTON, TEXAS.

COTTON, BERRY, OR VEGETABLE PICKING OR DAIRY STOOL.

SPECIFICATION forming part of Letters Patent No. 759,809, dated May 10, 1904.

Application filed July 20, 1903. Serial No. 166,269. (No model.)

To all whom it may concern:

Be it known that I, JOHN C. FARLEY, a citizen of the United States, and a resident of Ennis, in the county of Ellis, in the State of Texas, 5 have made certain new and useful Improvements in Cotton, Berry, or Vegetable Picking or Dairy Stools, of which the following is a specification.

My invention is an improvement in stools 10 for use in picking cotton, berries, vegetables, and the like and for dairy use and for other use where it is desirable or necessary to stoop over and to have the hands free to perform the work.

15 The invention has for an object to provide a simple inexpensive construction which can be conveniently secured to the person of the wearer, can be conveniently adjusted to form a stool of any desired height, will not interfere with the wearer walking from place to place as may be desired in the work, and will readily adjust to position for use when the operator stoops over, as in the act of milking or 20 picking berries, vegetables, cotton, or other 25 objects near the ground; and the invention consists in certain novel constructions and combinations of parts, as will be hereinafter described and claimed.

In the drawings, Figure 1 illustrates the 30 improved stool as in use. Fig. 2 is a detail perspective view of the stool. Fig. 3 is a vertical longitudinal section of the stool, and Fig. 4 is a cross-section on about line 4 4 of Fig. 3.

35 As before suggested, I aim in constructing my stool to secure great simplicity, cheapness of construction, ease of adjustment to different heights, lightness, the greatest strength with the least weight, and to so form the seat 40 of the stool as to render the same comfortable for the wearer, both in sitting down on the stool and in walking with the stool connected with the wearer, and also to so form said seat as to prevent it shifting from side to side and 45 to insure its proper location when the wearer desires to sit down.

In the construction shown I prefer to make the stool of sheet metal—such, for instance, as galvanized iron—forming the stool in two

sections, the upper section carrying the seat 50 A and the lower section the foot B, and the leg of the stool being made in two sections C and D, connected, respectively, with upper and lower sections of the stool, as shown in Figs. 2 and 3. The upper section A is formed 55 with the seat E and with the tapered base portion F, the latter sloping gradually from its lower end f, where it is secured to the leg-section C to its upper outer edge, where it unites at f' with the outer edge of the seat E. 60 The leg-section C, being secured at f' by soldering or otherwise, extends upward within the base portion F and is secured at its upper end at C' by soldering or otherwise to the under side of the seat E, so that the seat is 65 supported directly on the leg of the stool, and the base portion F forms a brace to give the necessary strength to the outer edge of the seat E without necessitating the making of 70 said seat so thick and heavy as would otherwise be necessary.

The seat E is curved generally to fit the wearer and is provided with the forwardly-projecting horn A', which curves slightly upward toward its front end and fitting between 75 the legs of the wearer co-operates with the side arms A², which extend up at the opposite sides of the seat, in preventing any lateral shifting of the seat and preserves the stool in proper position to support the wearer whenever he leans over when in the act of picking cotton and the like, as will be understood in Fig. 1. The arms A² are provided at their upper ends with the loops a², to which are secured the side straps G, connected with the 80 belt H, fitting around the waist of the wearer in the use of the invention, as shown in Fig. 1. By means of the side straps, the side arms A², and the horn A', I prevent any lateral 85 shifting of the stool and preserve the same in 90 proper position upon the wearer for use in the manner before described.

The foot B is in the form of a truncated cone whose broad base B' rests upon the ground, and the leg-section D is secured by 95 soldering or otherwise at d to the upper end of the foot B and extends within the said foot and rests at its lower end upon the bottom

B', thus increasing the strength of the lower section of the stool, as will be understood from Fig. 3 of the drawings.

The section D of the leg telescopes within 5 the section C and is provided with a series of perforations d' to receive the pin I', carried on the lower end of the spring I, whose upper end is secured at i to the leg-section C, the pin I' passing through an opening in the 10 leg-section C and into one of the perforations d' in the leg D, as shown in Fig. 3. By preference the leg-sections C and D are made rectangular in cross-section in order to secure the greatest strength of the parts and also to 15 insure the arrangement of the perforations d' in position to be entered by the pin I' in the use of the invention. When desired, the pin I' may be sprung out of any particular hole d' to permit the adjustment of the leg to 20 lengthen or shorten the same, as may be desired.

Having thus described my invention, what I claim as new, and desire to secure by Letters Patent, is—

25 The improved stool herein described comprising the upper section having the seat pro-

vided with the forwardly-projecting horn and at its opposite sides with the upwardly-projecting arms, the fastening-straps secured to said upwardly-projecting arms, the base portion for the seat tapering upward from its lower to its upper edge and secured at its upper edge to the seat, the upper leg-section secured to the lower end of the base portion of the seat and extending upwardly within said 30 base portion and secured at its upper end to the under side of the seat, the spring-latch secured to the upper leg-section and having a pin to engage the lower leg-section, said leg-section being square in cross-section and the 35 lower stool-section having the foot in the form of a truncated cone and the lower leg-section extending within said foot and secured to the bottom and upper end thereof and fitting in the upper leg-section and provided with a series of perforations for engagement by the 40 latch-spring thereof substantially as set forth. 45

JOHN C. FARLEY.
